No. 769,414.

PATENTED SEPT. 6, 1904.

G. SIMMONS.

SPLIT PULLEY.

APPLICATION FILED OCT. 19, 1903.

NO MODEL.

UNITED STATES PATENT OFFICE.

GUY SIMMONS, OF COLUMBUS, OHIO.

SPLIT PULLEY.

SPECIFICATION forming part of Letters Patent No. 769,414, dated September 6, 1904.

Application filed October 19, 1903. Serial No. 177,675. (No model.)

To all whom it may concern:

Be it known that I, GUY SIMMONS, a citizen of the United States, residing at Columbus, in the county of Franklin and State of Ohio, have invented certain new and useful Improvements in Split Pulleys; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in split pulleys and comprises means whereby the two sections of the wheel may be easily and quickly put together and taken apart; and it consists specifically in the provision of hooked rods having threaded ends to be engaged by nuts and which pass through cross-pieces upon the sections of the pulley and in the provision of cams which engage the hooked ends of said rods and are adapted to draw the two sections taut as said cams are turned frictionally against the sections of the pulley.

The invention consists in various details of construction and in combinations and arrangements of parts, which will be hereinafter fully described and then specifically defined in the appended claim.

My invention is illustrated in the accompanying drawings, which, with the letters of reference marked thereon, form a part of this application, in which—

Figure 1 is a side elevation of my improved pulley. Fig. 2 is a sectional view through the pulley. Fig. 3 is a detail sectional view through portions of the sections, and Fig. 4 is a detail view of one of the rods upon which a cam member is adapted to be mounted.

Reference now being had to the details of the drawings by letter, A and A' designate two complementary sections of the pulley, one end of each of which sections has a tongue or slightly-projecting portion *a*, which is adapted to enter a recess *a'* in the other end of each adjacent section of the pulley, said recess or depression being of such a shape as to con-

form to said tongue or projection. Each section of the pulley has a cross-piece B, adapted to engage a shaft, and registering apertures C are formed through said cross-pieces and are provided for the reception of the rods D, each of which has an angled end D' and a straight threaded end F for the reception of tightening-nuts E. A cam-lever K, having an aperture K', is adapted to engage each hooked end of the rod, and interposed between each cam member and the adjacent cross-piece of the pulley-section is a washer T, against which the cam is thrown in order to hold the two sections frictionally together. In applying the rods to the pulley-sections I prefer to arrange the rods in reverse order, one cam-lever bearing against each cross-piece of a section of the pulley, whereby the two sections may be securely clamped together. By reason of the nuts mounted upon the threaded ends of the rods it will be noted that the two sections may be readily adjusted, so that means is provided for taking up any shrinkage or variation in the cams of the pulley, and it will further be noted that by the provision of a pulley embodying the features of my invention the same may be easily and quickly applied to and removed from a shaft.

While I have shown a particular construction of pulley embodying the features of my invention, it will be understood that I may make alterations, if desired, in the details of construction of the same without in any way departing from the spirit of the invention.

Having thus described my invention, what I claim as new, and desire to secure by Letters Patent, is—

A split pulley, comprising two complementary sections having tongue-and-groove connections, cross-pieces having contracted ends jointed into the sections adjacent to the ends thereof, said cross-pieces having their widened central portions concaved and designed to receive a shaft to which the pulley is adapted to be clamped, angled rods having threaded ends passing through registering apertures in said cross-pieces, adjacent to the marginal ends of said recesses, a nut mounted upon the threaded end of each rod, a cam member piv-

totally mounted upon the angled end of each of said rods, the free end of each of said cam members being inclined and having each a projection which is adapted to contact with 5 one of said cross-pieces, whereby said cam members may be held parallel with the cross-pieces, when in clamping relation, as set forth.

In testimony whereof I hereunto affix my signature in presence of two witnesses.

GUY SIMMONS.
